ATTORNEY

UNITED STATES PATENT OFFICE.

WILLIAM D. PYLE, OF INDIANAPOLIS, INDIANA.

CIRCUIT-PROTECTIVE DEVICE.

1,272,090.

Specification of Letters Patent.

Patented July 9, 1918.

Application filed July 10, 1917. Serial No. 179,740.

To all whom it may concern:

Be it known that I, WILLIAM D. PYLE, a citizen of the United States, residing at Indianapolis, in the county of Marion and 5 State of Indiana, have invented new and useful Improvements in Circuit-Protective Devices, of which the following is a specification.

This invention relates to improvements in 10 devices for protecting electric circuits from excessive currents, and has for its objects to provide a simple, substantial, and efficient device which may be used an indefinite number of times without renewal. It is further 15 proposed to incorporate in the device means whereby the circuit will be permanently interrupted following the operation of the device until it is manually restored to normal condition.

20 From the description below taken in connection with the drawings, the construction and operation of the device will be readily understood.

In the drawings—

25 Figure 1 is a side elevation.

Fig. 2 is a longitudinal section through the device.

Fig. 3 is a transverse section on the line 3—3 of Fig. 2.

30 Fig. 4 is a section on line 4—4 of Fig. 2.

In the present invention a column of conducting liquid, preferably mercury, constitutes the circuit-breaking element.

As shown in the drawings, the device comprises a hollow cup-like body 1 of conducting material, preferably metal, and adapted for connection to one side of a circuit. The body is formed in the inner surface of the bottom with concentric annular grooves or 35 channels constituting respectively a mercury reservoir 3 and a pocket 4 for directing mercury entering the pocket into an opening 5 extending from the bottom of the pocket through the bottom of the body. The reservoir 3 is desirably of a larger capacity than the pocket 4 and reduced in width toward the bottom as shown.

For displacing the mercury in the reservoir 3 to cause it to overflow into the pocket 4, a plunger 6 loosely inserted in the body 1 has a flange adapted to enter the reservoir 3, the flange being preferably of suitable shape to conform to and completely fill the reservoir, thus enabling all the mercury to be utilized. The head of the plunger 6 is attached to a shank 7 slidably mounted in a

cap 8 screwthreaded on the end of the body 1 and is terminally provided exteriorly of the cap with a head 9 for manual actuation. A spring 10 bearing against the cap 8 and head 9 is provided for withdrawing the plunger 6 from the reservoir 3; and vents 11 provided in the plunger 6 prevent formation of a partial vacuum in withdrawing the plunger from a completely depressed 65 position.

The body 1 is formed in the bottom centrally to the pocket 4 with an opening 12 for receiving the reduced extension of a cylindrical plug 13 of insulating material 70 inserted in the end of an insulating shell or tube 14 attached outwardly of the bottom, as here shown by screwthreaded engagement with a collar provided on the bottom.

Tightly inserted in the other end of the tube 14 is a conducting plug 15 adapted for connection to the other side of the circuit. The insulating plug 13 is formed with a bore 16 establishing connection at one end 80 with the opening 5 communicating with the pocket 4, and at the other end with the adjacent cavity 18 in the tube; and is further formed with a bore 19 extending through the extension and constituting a vent for the 85 cavity 18.

It will be seen that in the actuation of the plunger the mercury will enter the bores in the plug 13 and the cavity 18 in the tube, and establish connection between the body 1 90 and plug 15. The bore 16 is properly proportioned to the maximum current to be carried by the device, so that the contained column of mercury will be partially vaporized when overloaded, and the mercury forcibly expelled from the bores to be retained by the reservoir 4 until the plunger 6 is manually actuated to reestablish the circuit.

It will be evident that the preferred form of the invention described and shown constitutes only one of many possible embodiments, and the right is reserved to such variation and use of equivalents as falls within the spirit of the invention and the latitude of the claims.

105 What I claim is:

1. A safety device for an electric circuit comprising a tube, a body mounted on one end of the tube, said body formed with a pocket in connection with the bore of the 110 tube and further formed with a reservoir adapted for containing a quantity of liquid,

means for displacing liquid in the reservoir to cause the liquid to enter the pocket and fill the tube, and means for establishing electric connection with liquid in the tube.

- 5 2. A safety device for an electric circuit comprising a tube, a body mounted on one end of the tube, said body formed with a pocket in connection with the bore of the tube and further formed with a reservoir
10 adapted for containing a quantity of liquid, means for displacing liquid in the reservoir to cause the liquid to enter the pocket and flow by gravity into the tube, means for establishing electric connection with the liquid
15 in the tube, and means whereby liquid expelled from the tube will be directed to enter the reservoir.
3. A safety device for an electric circuit comprising a tube formed with a pair of bores, means on one end of the tube inclosing a cavity connecting said bores, a conducting body mounted on the other end of the tube, said body formed with an annular pocket surrounding one of the bores and establishing connection with the other bore, said body further formed with an annular
20
25

reservoir surrounding said pocket and adapted for containing a quantity of liquid, means for displacing liquid in the reservoir to cause the liquid to enter the pocket and fill the bore connected with the pocket and means whereby liquid expelled from the bores of the tube will be directed to enter said reservoir.

4. In an electric protective device, a cylindrical body closed at one end with a bottom and provided on the bottom with an upstanding annular rim, and formed in the bottom with a pair of openings terminating in the space within the rim; an insulating tube attached to the body exteriorly of the bottom and formed with a pair of bores establishing connection with the openings in the body, and a cap on the tube inclosing a cavity connecting the ends of the bores; a cap on the body, a headed shank slidably inserted in an opening in the cap, and a plunger in the body attached to the shank and adapted for entering the space between the wall of the body and the rim.

In testimony whereof I affix my signature.
WILLIAM D. PYLE.
